United States Patent Office

Des. 195,733
Patented July 23, 1963

195,733

TAPE RULE

Neil G. Kane, Santa Fe Springs, Calif., assignor to H. K. Porter Company (Delaware), Danville, Va., a corporation of Delaware

Filed Nov. 13, 1962, Ser. No. 72,482

Term of patent 14 years

(Cl. D52—1)

FIG. 1

FIG. 2

The essential features of the design reside in the casing shown in full lines.

I claim:

The ornamental design for a tape rule, substantially as shown and described.
